UNITED STATES PATENT OFFICE.

JOHN F. HURD, OF BROOKLYN, NEW YORK, ASSIGNOR TO METROPOLITAN-COLUMBIA MFG. CO., INC., A CORPORATION OF NEW YORK.

DESIGN FOR A LIGHTING-FIXTURE CANOPY OR ANALOGOUS ARTICLE.

Application filed May 14, 1927. Serial No. 21,980. Term of patent 3½ years.

To all whom it may concern:

Be it known that I, JOHN F. HURD, a citizen of the United States, and a resident of Brooklyn, county of Kings, and State of New York, have invented a new, original, and ornamental Design for a Lighting-Fixture Canopy or Analogous Article, for which the following is a specification, reference being had to the accompanying drawings, forming a part hereof.

The figure in the drawing shows a perspective view of the lighting fixture canopy or analogous article.

I claim:

The ornamental design for a lighting fixture canopy or analogous article substantially as shown.

JOHN F. HURD.
